[57] **CLAIM**

The ornamental design for a vehicle tire tread, as shown and described.

DESCRIPTION

FIG. 1 is a perspective view of a vehicle tire tread showing my new design, it being understood that the tread pattern is repeated uniformly throughout the circumference thereof;

FIG. 2 is a front elevation view thereof; and,
FIG. 3 is a side elevation view thereof on a reduced scale, it being understood that the opposite side is a mirror of that shown.

The broken line showing of the tire sidewall in FIGS. 1 and 3 of the drawing is for illustrative purposes only and forms no part of the claimed design.
